OIL BLAST CIRCUIT BREAKER

William Anselm Coates, Bowdon, England, assignor to General Electric Company, a corporation of New York

Application January 5, 1934, Serial No. 705,448
In Great Britain January 18, 1933

9 Claims. (Cl. 200—150)

This invention relates to electric switches or circuit breakers of the fluid-blast type wherein the switch contacts are immersed in an insulating fluid, as oil, and arranged to provide a plurality of breaks in series, the arc where the circuit is actually to be broken being extinguished by a blast of oil produced by pressure generated by a preliminary or pressure-generating arc occurring between auxiliary contacts within an explosion pot.

When such a switch is employed for breaking small currents, for example at very high voltage, the pressure-generating arc formed between the auxiliary contacts may not produce sufficient energy to cause an effective oil blast for extinction of the main arc, while the voltage may be high enough to enable the arc to persist unless it is extinguished at an early stage of its formation.

A principal object of the present invention is the provision of an improved circuit breaker of the aforesaid type which shall be simple in construction and reliable, positive and efficient in operation.

According to the present invention a plurality of preliminary or pressure-generating breaks in series are caused to occur simultaneously in the explosion pot so that the oil blast is directed by sufficient pressure to extinguish the arc occurring on the final break.

This invention will be more fully set forth in the following description referring to the accompanying drawing, and the features of novelty which characterize the invention will be pointed out with particularity in the claims annexed to and forming a part of this specification.

Referring to the drawing, Fig. 1 is an elevational sectional view of oil-blast, explosion-pot circuit breaker structure embodying the present invention; Fig. 2 is a reduced plan sectional view taken along the line II—II of Fig. 1; Fig. 3 is a reduced plan sectional view taken along the line III—III of Fig. 1; and Fig. 4 is a similar view of another form of my invention.

In carrying out the invention according to a preferred arrangement thereof the preliminary or pressure-generating breaks in the circuit may be arranged to occur in a single closed vessel or explosion pot filled with oil, and the rise in pressure due to the arcs formed therein causes flow of oil from said explosion pot through a passage adjacent the place where the final break in the circuit occurs, the oil flow being preferably across the arc in the form of a multiple jet.

It will be understood that the explosion pot arrangement shown in Fig. 1 will be located in

an oil tank and rigidly mounted, such as upon the main terminal lead-in conductor 1, usually side by side with another similar arrangement (not shown). The two explosion pots are arranged to be interconnected by a moving bridge 5 (also not shown) which has a pair of upstanding rod or plug contacts, one of which is shown at 2 in the open circuit position. The plug 2 in order to close the switch is adapted to travel through a vertical passageway indicated at 3 10 which is intersected by a plurality of transverse passageways 4 which, along with the passageway 3, are formed in insulating material in generally known manner. At their right hand ends as viewed these passageways 4 communicate with 15 an opening 5 in an outer insulating cylinder 6 and at their left hand ends they communicate with a vertical channel 7. The passageways 4 are bounded at the top by an insulating member 8 and at the bottom by another insulating member 9.

For the purpose of obtaining a multiplicity of breaks in series the contacts which are first separated when the circuit is to be interrupted are constructed so that when the contacts are in engagement the current passes backwards and forwards from one contact to another a number of times whereby when the contacts are separated a number of comparatively short breaks will occur in the circuit in series. As the amount 30 of heat energy transferred to the oil by the arc is dependent upon the length of the arc as well as the current it will be seen that by the present arrangement the total length of the arc is increased in proportion to the number of preliminary breaks although the current carried by the arc may be small. The path of the current from contact to contact may be non-linear, that is in the form of a zigzag, or may form a series of closed loops.

In some cases the component parts or pairs of the contacts between which the arcs are formed may be spaced apart in a graduated manner, in which case with larger currents some of the arcs 45 which are located closely adjacent to each other will coalesce. This is a desirable feature as the pressure available for directing the oil blast will be graduated to some extent automatically. If the pairs of series of contacts are spaced apart 50 in a progressively increasing manner, for example, individual arcs will be formed between the pairs of contacts when very small currents pass, while two or three or more of the arcs may coalesce when a larger current passes, thereby auto- 55

matically reducing the arc pressure at large or short circuit currents.

The moving contact 2 is adapted to engage a main contact 10 which is carried on a rod 11 vertically slideable with respect to the insulating member 8. The rod 11 is secured at its upper end to a carrier 12 for a plurality of movable auxiliary contacts which cooperate with a corresponding number of fixed auxiliary contacts. 10 The auxiliary arcs are formed in series before the moving contact 2 separates from the fixed contact 10 between which the final or main arc is drawn, the arc being quenched by the blasts of oil or a mixture of gas and oil flowing through the transverse passageways 4 from the vertical channel 7 from the upper explosion pot or chamber 13 in which the aforesaid series preliminary arcs take place. It is to be understood that since the arrangement shown in Fig. 1 is immersed in oil its interior will be normally full of oil so that the oil in the upper explosion pot 13 will be forced therefrom by the preliminary arcs.

The fixed contacts for the preliminary arcs in the arrangements shown are seven in number 25 and are indicated respectively at 14 to 20, inclusive, as will readily be seen from Fig. 2, but two thereof, 14 and 18, being visible in Fig. 1. The contact 14 is connected by means of a radial conducting strap 21 with a central conductor 22 which is connected with the main terminal conductor 1. The contacts 15 and 16 are connected by a tangential strap 23. The contacts 17 to 20, inclusive, are likewise connected in pairs by conducting straps 23. The contacts 14 to 20 and the 30 members 21, 22 and 23 are conveniently moulded in a block 24 of insulating material such as a phenolic condensation product. The contacts 14 to 20 are preferably exposed at the upper ends of respective recesses 25 in the insulating block 24. The angles between the pairs of contacts 14-15, 15-16 . . . 19-20 may be equal, as shown, or they may be graded as and for the purpose hereinbefore set forth. Fig. 4 illustrates such an arrangement, the movable contacts 26 to 32 inclusive, and the corresponding stationary contacts (not shown) being spaced so that some of the more closely positioned arcs are short-circuited at heavy currents and the arc length and pressure accordingly reduced.

50 The moving auxiliary contacts are indicated at 26 to 32, inclusive. They are formed or provided with stem portions 33 slideable in holes in the upper portion of the carrier 12 which is made in two parts adapted to be rigidly secured together, the upper of which is shown at 34 and the lower portion thereof at 35. These portions 34 and 35 may also be made of moulded insulating material. The upper portion 34 is also provided with tubular guide portions 36 for the contacts 26 to 32 and also with recesses 37 on the under side to accommodate heads 38 on the stems 33. The recesses 37 are connected in consecutive pairs by linking channels 39, as indicated by dotted lines in Fig. 3. The recess 37 for the contact 32 has a linking channel 40 communicating with the upper end of the contact 11. Within these channels 39 and 40 are accommodated conductors 41, only parts of two of which are visible in Fig. 1, for connecting together respectively the moving auxiliary contacts 26 and 27, 28 and 29, 30 and 31, and the contact 32, and the main contact 10. The contacts 26 to 32 are biased upwards with respect to the carrier 12 by means of springs 42.

75 A spring 43 is interposed between the main

contact 10 and the upper end of a recess 44 in the insulating member 8, the arrangement being such that the carrier 12 is normally retained by the spring 43 in the lower position illustrated, but is capable of being raised by the moving main contact 2 when the latter engages the coating contact 10, until the contacts 26 to 32 engage respectively the contacts 14 to 20, the contacts 26 to 32 moving as necessary, relatively to the carrier 12 by reason of the biasing springs 42.

10 With the arrangement described it will be appreciated that current flowing down the main terminal conductor 1 will, as indicated by the short arrows in Fig. 1 and by Figs. 2 and 3, flow from the member 22 first down through the fixed contact 14 to the contact 26, upwards through the moving auxiliary contact 27, the fixed contact 18, the strap 23, the fixed contact 16, downwards to the moving auxiliary contact 28 and so on and finally from the moving contact 32 to the main contact 10 and the main moving contact 2.

Upon the opening of the circuit breaker it will be appreciated that by reason of the arrangement, the pairs of auxiliary contacts 26-14, 27-15 . . . 32-20 will separate simultaneously before the contacts 2 and 10 start to separate, and the joint effect of the seven preliminary arcs in the chamber 13 will cause a powerful blast of oil to flow, as indicated by the chain arrows in Fig. 1, from this chamber down the channel 7 and through the cross jet passages 4 so as to be effective in quenching the arc between the main contacts 2 and 10 in the vertical passage 3.

In a convenient constructional form of the 35 invention the bottom of the explosion pot through a passage in which the movable contact of the switch is arranged to move when making and breaking the circuit may comprise a series of plates spaced apart so as to form transverse passages through which a flow of oil or oil and vapor is caused by reason of the pressure arising in the explosion pot. These arrangements are well known and various constructional forms have been employed. The switch contacts for 40 obtaining the several preliminary breaks in series and the connecting members of these contacts may be embedded in and insulated as necessary from each other by a suitable insulating material moulded to suitable form.

45 It should be understood that this invention is not limited to specific details of construction and arrangement thereof herein illustrated, and that changes and modifications may occur to one skilled in the art without departing from the 50 spirit of my invention.

What I claim as new and desire to secure by Letters Patent of the United States, is:—

1. An electric circuit breaker of the oil-blast type for interrupting high tension power circuits, 55 comprising means forming a chamber containing an insulating liquid, relatively movable contact structure in said chamber including means forming a plurality of breaks in series at which preliminary pressure-generating arcs are formed, and means forming exteriorly of said chamber a main arc in series with the aforesaid arcs, the pressure generated by said preliminary arcs combining to direct a blast of insulating liquid from said chamber across said main arc.

2. An electric circuit breaker of the oil-blast type for interrupting high tension power circuits, comprising an explosion chamber pot containing an insulating liquid, relatively movable contact structure disposed within said pot including a

70
75

- plurality of pairs of contacts connected in series for forming a plurality of pressure-generating arcs, and contacts connected in series with the aforesaid contacts between which the arc to be interrupted is formed, and means directing the combined pressure of said pressure-generating arcs so as to cause a blast of insulating liquid through the arc to be interrupted and from said pot.
10. 3. An electric circuit breaker of the oil-blast type, comprising means forming an explosion chamber, an arc-extinguishing liquid within said chamber, relatively movable contact structure disposed within said chamber including pressure-generating contacts, and main current-interrupting contacts connected in series with the aforesaid contacts, said current-interrupting contacts subjected to a blast of said liquid from said chamber in response to generation of arcing pressure therein, said pressure-generating contacts including a plurality of pairs of contacts unequally spaced with respect to each other so that there is a tendency on the part of large arc currents to short circuit one or more of the pressure-generating arcs.
4. An electric circuit breaker of the oil-blast type, comprising means forming an explosion chamber, insulating liquid within said chamber, relatively movable contact structure disposed within said chamber including a plurality of pairs of contacts connected in series for producing pressure in said chamber, and contacts connected in series with the aforesaid contacts for interrupting the current, said pairs of pressure-generating contacts being arranged in said explosion chamber so that the total length of the pressure-generating arc is automatically shortened at heavy currents and so that the combined pressure thereof serves to direct a blast of insulating liquid between the current-interrupting contacts.
5. An electric circuit breaker of the oil-blast type, comprising means forming an explosion chamber, an arc-extinguishing liquid in said chamber, means in the circuit to be interrupted causing arcing in said chamber for generating pressure therein, said means positioned in the circuit along a non-linear path so that the arc length is in part automatically short-circuited at heavy arc currents, means forming a main arc in said circuit, and means for directing the pressure in said chamber so as to cause a blast of arc-extinguishing liquid through said main arc.
6. An electric circuit breaker of the oil-blast type for interrupting high tension power circuits, comprising an explosion chamber pot, an insulating liquid filling said pot, relatively movable contact structure disposed within said pot comprising a movable rod contact, an intermediate butt contact, a plurality of contacts carried by and movable with said intermediate contacts, a

plurality of coacting stationary contacts arranged to form with said movable contacts a plurality of breaks in series, said pairs of contacts disposed in a single pressure-generating chamber in said pot, and means directing the pressure from said chamber so as to cause a blast of insulating liquid from the same and through the arc formed between said intermediate and rod contacts.

7. An electric circuit breaker of the oil-blast type, comprising means forming an explosion chamber, an insulating liquid filling said chamber, relatively movable contact structure for generating arcing pressure in said chamber and for forming a main arc subject to a blast of insulating liquid from said chamber including a movable rod contact, an intermediate contact, a plurality of contacts carried by and movable with said intermediate contact, said plurality of contacts arranged generally in a circle, a plurality of coacting stationary contacts positioned in a corresponding manner and arranged to form with said movable contacts a plurality of breaks in series, said pairs of contacts disposed in said chamber and positioned in varying angular relationship so that one or more of said pairs are short circuited by heavy arc currents, and means directing the pressure from said chamber so as to cause a blast of insulating liquid through the main arc formed between said intermediate and rod contacts.

8. An electric circuit interrupter of the fluid-blast type for high tension power circuits, comprising means for causing arcing and generation of pressure within an arc-extinguishing fluid in the circuit opening operation, said means normally forming an appreciable arc length for generating pressure at low current values, said means arranged so that shortening of the arc by short circuiting of a part of the same takes place at comparatively high current values, means forming another arc in said circuit, and means for directing said pressure so as to cause a blast of arc-extinguishing fluid through said last-named arc.

9. An electric circuit breaker of the fluid-blast type for interrupting high tension power circuits, comprising relatively movable contact structure for causing arcing and the generation of pressure within an arc-extinguishing fluid in the circuit opening operation, said contact structure normally forming an appreciable arc length for generating pressure at low current values and arranged so that said contact structure is short circuited in part by the arc current at comparatively high current values for reducing said arc length, means forming another arc in said circuit, and means for directing said pressure so as to cause a blast of arc-extinguishing fluid through said last-named arc.
